US00D896200S

(12) **United States Design Patent** (10) Patent No.: **US D896,200 S**
(45) Date of Patent: **** Sep. 15, 2020**

(54) **EARPHONES**(71) Applicant: **Apple Inc.**, Cupertino, CA (US)(72) Inventors: **Ryan Ott**, North Hollywood, CA (US); **Carlos M. Santana**, Granada Hills, CA (US); **William R. Rochowicz**, Manhattan Beach, CA (US); **Robert Boyd**, Los Angeles, CA (US); **Martin Gschwandt**, San Francisco, CA (US); **Guillaume Raoult**, San Francisco, CA (US); **Christopher Kuh**, San Francisco, CA (US); **Robert Brunner**, Glen Allen, CA (US)

(Continued)

Primary Examiner — Paula Allen Greene*(74) Attorney, Agent, or Firm* — Sterne, Kessler, Goldstein & Fox, P.L.L.C.(57) **CLAIM**

The ornamental design for earphones, as shown and described.

DESCRIPTION

FIG. 1 is a top front perspective view of earphones showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.
